UNITED STATES PATENT OFFICE.

BIRD H. SHARP, OF VICTORIA, TEXAS.

GAME-CARDS.

SPECIFICATION forming part of Letters Patent No. 706,603, dated August 12, 1902.

Application filed May 29, 1901. Serial No. 62,480. (No model.)

To all whom it may concern:

Be it known that I, BIRD H. SHARP, a citizen of the United States, residing at Victoria, in the county of Victoria and State of Texas, have 5 invented new and useful Improvements in Game-Cards, of which the following is a specification.

This invention relates to new and useful improvements in game-cards; and its object is 10 to provide a pack of playing-cards or game-cards which are attractive and instructive and whereby suitable games may be played.

With these and other objects in view the invention consists of a deck of novel cards, 15 such as hereinafter more fully described and claimed, and illustrated in the accompanying drawings.

A full pack comprising my invention consists of forty-eight cards arranged in three 20 suits, representing the United States, Spain, and Cuba, respectively. Each suit contains ten cards numbered from "1" to "10" and having the ensign of one of the above countries thereon. By means of these ensigns it 25 can be readily determined to which suit the cards belong. Three other cards are arranged in each suit, and in addition to the ensigns displayed thereon they contain representatives of officers of three degrees of rank, one 30 being shown upon each card. These officers are preferably prominent personages, and the rank of each is indicated in the corner of the card. The United States and the Spain suits are each completed by three cards bearing 35 representatives of well-known war vessels and are distinguished from each other by means of ensigns, as are the other cards of the pack. The Cuban suit is completed by three cards, each bearing a representation of 40 one of three well-known Cuban harbors or fortresses.

It will be seen from the foregoing that each suit comprises sixteen cards and that the three suits are distinguished from each other 45 principally by the ensigns of the three countries represented.

The representatives upon the six higher cards of each suit are preferably duplicated and arranged so as to be read from either end 50 of the cards.

The cards representing the vessels are numbered from "1" to "3" in each suit.

In the accompanying drawings, Figure 1 is a view of a captain card of one country. Fig. 2 is a view of a colonel card of a second country. Fig. 3 shows a general card of the third country. Fig. 4 is a marine card for one of the two suits containing representations of war vessels. Figs. 5, 6, and 7 show ensign-flags for the three countries, and Fig. 8 is a 60 view of one of the marine cards of the suit which does not contain the vessels.

This pack of cards being composed of three suits or denominations have an unequal value in playing, as follows, namely: The United 65 States and Spain cards are of equal value naturally, though one suit being made trump-cards gives it predominance over the other, while the other suit is given precedence at any and all times over the third or Cuban 70 suit, excepting officers of said suit, which cards may be played with preference to the opposing suit (to trumps) all but the officers of opposing suit, though they are to follow even the flag cards of trump suit. The third 75 or Cuban suit is never used as trump-cards, but only in like manner to an allied nation in time of war. From lowest to highest card is as follows: The card representing a general is the highest card in the pack, next 80 comes the one representing the colonel, next captain, next the marine cards, number "1" being the highest, number "2" the second, number "3" the third. Then comes the flag cards as numbered from "10" to "1," "10" 85 being the highest. The marine cards are worth as much for scoring for game as are the officers, although they are of lower degree relatively.

This pack being composed of forty-eight 90 cards and made up of three suits, each suit represented by sixteen cards, has, according to the value placed on the face-cards, a total (in scoring for game) of one hundred and eighty. The cards are valued as follows, 95 viz: The general has a counting value of fifteen, colonel ten, and captain five. The marine representatives are as follows: No. 1 has a counting value of fifteen, No. 2 ten, and No. 3 five. The flag cards have no intrinsic 100 value, except for sake of play, which may be governed by the discretion of player.

One being selected as first dealer in any satisfactory manner takes the cards and shuffles well, after which they are offered to the first player to the right to be cut, which is done by taking not less than five cards from top to be placed on bottom of deck. This 5 being done, dealing proceeds by commencing at left and dealing three cards to each player. This being repeated twice gives each player nine cards. The next thing in order is to pitch a trump, which is done by each player bidding 10 for trump, that privilege being given to highest bidder. The bidding is governed by the counting value of bidder's hand. However, if the bidder holds as much as two high cards of either of the suits that may be made trumps 15 he can afford to bid to the very utmost of his counting-hand. The trump is set or made known by proposing to defend Cuba with the United States or Spain cards, as the case may be. For example, you propose the defense 20 of Cuba with Spain, thereby making the Spain cards the trump, which puts the Cuban officers trump-cards with Spain, though below even the lowest Spanish card. However, they retain their counting value in all cases. 25 In the above example the Cuban officers dominate over the United States cards all but the United States officers, which are always superior to any Cuban card, and even all the rest of the United States cards pre- 30 dominate over the Cuban cards, all but the officers. After the trump is made known the first player (the one who set the trump) may start the game by playing any card he chooses, each player following suit until all 35 have played, the highest card being entitled to the trick. The one taking the trick is put in the lead for the next play, and so on until all the cards have been played. Then the count is scored for game. The game may be 40 set at one hundred and eighty (180) or two hundred and fifty (250) at will of the participants in the game. When a trump is made known by the highest bidder, he and partner must make a scoring count to equal that of bid or else forfeit that amount from 45 previous game score, or if there be no game score they will owe that amount, which must be paid. If a misdeal should be made by accident or otherwise, the cards shall be passed to next player to deal, he thereby forfeiting his right to deal until the deal goes around and back to him. Then he may have equal rights, as before. Slipping a card from the pack is a misdemeanor that is not in keeping with good social culture. Each leading 50 card of a trick must be followed in suit, if possible, unless players choose to play a trump-card.

In playing single-handed by two or three the game may be conducted in like manner 60 to that of playing partners, only that each one must depend entirely on his own hand when bidding for the lead or trump, while in four-handed games the bidder can depend on his partner's hand to a certain degree, providing the bidder should hold high-scoring 65 and superior cards. In single-handed game the game-score may be put at one hundred and fifty, making it possible to play a game in two deals.

Having thus fully described my invention, what I claim as new, and desire to secure by Letters Patent, is—

A pack of playing-cards made up of three suits of three groups each, each suit representing a country and comprising a group of consecutively-numbered similar cards, a second group of cards of different values, said values being indicated by pictures on the cards, and a third group of consecutively-numbered cards bearing similar pictures thereon.

In testimony whereof I affix my signature in presence of two witnesses.
